UNITED STATES PATENT OFFICE.

CHARLES P. LANCASTER, OF JONESBORO, INDIANA, ASSIGNOR OF ONE-HALF TO JOSEPH C. STOEBE, OF MARION, INDIANA.

RAIL-JOINT.

No. 916,880.

Specification of Letters Patent. Patented March 30, 1909.

Application filed June 1, 1908. Serial No. 436,000.

To all whom it may concern:

Be it known that I, CHARLES P. LANCASTER, a citizen of the United States, residing at Jonesboro, county of Grant, and State of Indiana, have invented certain new and useful Improvements in Rail-Joints, of which the following is a specification, reference being had, therein to the accompanying drawings, in which—

10 Figure 1 is a perspective view of the joint applied; Fig. 2 a similar view showing the swinging clamping member disengaged from the rail ends; Fig. 3 a vertical transverse sectional view of the joint in position on a rail; Fig. 4 a perspective view of the rigid member of the joint; Fig. 5 a perspective view of the swinging clamping member of the joint; and Fig. 6 a detail sectional view showing the hinged joint between the swinging member and the rigid main member.

One of the main objects of this invention is to provide a rail joint of two members to serve as a rigid clamping means for the adjoining ends of two railroad rails, and where- 25 by the usual bolts and nuts are dispensed with, the members of the joint being so constructed that any weight applied to the rails will serve to cause said members to bind 30 against said rails and to securely hold them in alinement.

Another object of the invention is to so construct the members of the joint that they will be rigidly locked together against displacement when the rail is in position on the 35 ties, and wherein the rail must be elevated from the ties before the members of the joint can be detached from the rail.

A further object of the invention is to provide means for locking the swinging clamp- 40 ing member to the rigid main member to prevent accidental displacement thereof, or the disconnection of said swinging member from the main member.

Other important objects and advantages 45 of the invention will be apparent to those skilled in the art to which this invention appertains, and need not be specifically set forth herein.

Referring to the various parts by numer- 50 als, 1 designates the rigid main member of the joint, and it consists of the broad flat base support 2 which fits under the adjoining ends of two rails, bridging the joint between them and forming a very strong and rigid

support, therefor. This is important as it 55 supports the two rails at the same level and effectually prevents any sagging of one rail under the constant pounding of the car wheels. Along one edge of this base support is formed the inwardly and upwardly ex- 60 tending flange 3 which fits over the base of the rail, and at the inner upper end of said flange is formed the upwardly extending rail head supporting flange 4. The upper end of this flange is adapted to fit under the head of 65 the rail and to bridge the space between the base of the rail and said head to form a rigid support for the rail head. The base support 2 of the rigid member of the joint is considerably broader than the base of the rail so 70 that in its applied position, as shown in Fig. 1, the free edge of said base support extends a considerable distance beyond the longitudinal edge of the rail base. Along the free edge of said projecting portion of the base 75 support is formed an approximately cylindrical rib 5 which is raised slightly above the upper surface of the base support and is adapted to serve as one member of a hinge. Between this bead or rib and the adjoining 80 edge of the rail base, the base support 2 is provided with spike holes 6.

Hinged to the bead 5 of the rigid main member of the joint is a swinging clamping member 7. This clamping member consists of the substantially horizontal portion 8 which has a groove 9 formed in its under side and adapted to receive the bead 5. The horizontal portion 8 of the clamping member extends outwardly beyond the groove 9 and 90 forms a tie engaging portion 10. At the inner edge of the clamping member an upright rail clamping and supporting part 11 is formed, said part bridging the space between the rail head and the rail base. On 95 the inner side of this rail supporting portion of the clamping member are formed outwardly extending lugs 12 which are adapted to enter the bolt holes in the rail ends and to effectually lock the joint members to the 100 rails and to prevent the rails creeping or moving longitudinally through the joint. Spike holes 13 are formed in the horizontal portion 8 of the clamping member, said holes registering with the spike holes in the 105 base plate of the rigid member of the clamp, when the clamping member is swung inward into engagement with the rails. When

spikes are driven through these registering holes the two members of the joint are securely connected together and to the rails.

Formed on the hinge rib 5 is an inwardly and upwardly extending lug 14; and in the clamping member 7, adjacent to said lug, is formed a recess 15 which is adapted to receive the lug 14 when the clamping member is swung into engagement with the rails. It will be readily seen that in order to detach the clamping member from the rigid member, the clamping member must be swung outwardly to release it from the lug 14. In this position it may be slid longitudinally on the hinge rib to detach it from the rigid member.

The groove 9 in the swinging clamping member 7 is slightly more than semi-cylindrical so that the opening is slightly narrower than the widest part of said groove, the object being to prevent the lateral detachment of the swinging member from the rigid member. The hinge rib fits snugly within the groove 9 so that to detach the members they must be moved longitudinally with respect to each other. This is of importance as it prevents the lateral separation of the two members of the joint should the spikes be withdrawn or broken. The tie engaging portion 10 serves to hold the rail clamping and supporting part 11 in engagement with the rails and prevents any outward movement of said portion until the rails and joint have been raised sufficiently to permit the tie engaging part to swing downwardly.

The rail supporting flange 4 of the rigid member is provided on its inner side with horizontal lugs 16 which are adapted to enter the bolt holes in the rails and serve to position the joint members and to aid in preventing any creeping of the rails through the joint. It will, of course, be understood that if desired these lugs may be dispensed with. The rigid member of the joint is formed with spike holes near its outer edge so that the entire joint may be spiked to the ties in the ordinary manner. By extending the base support 2 of the rigid member a considerable distance beyond the adjoining edge of the rail, the said base support may be moved inwardly under the rail when the swinging member has been swung outwardly on the hinge, to free the flange 3 from the rail head, thus permitting the joint members to be readily detached from the rail.

It is manifest that any yielding or downward movement of the rails will cause the tie engaging part 10 to bear against the ties and the rail clamping portion 11 will be forced against the rail. It is also manifest that I provide an automatic clamping means whereby the rails may be connected together and rigidly held against longitudinal movement without the use of the usual bolts, nuts

and fish plates. By providing such a joint I avoid all of the difficulties occasioned in the ordinary type of rail joint by the expansion and contraction of the rails and the loosening of the bolts and nuts by reason of the jar of the passing trains. It is also clear that the rail joint cannot be loosened until the rails have been raised sufficiently to permit the swinging clamping member to be swung outwardly.

The clamp consists of two parts of simple construction which may be made out of any suitable material, such as cast or malleable iron, or they may be stamped out of steel.

It will be observed that the hinge bead 5 is turned upwardly so as to lie above the plane of the bottom of the rail base thus forming an upstanding abutment to receive the outward pressure occasioned by the clamping of the rail. Thus bringing the axis of the hinge above the plane of the bottom of the rail base necessitates that the supporting plate 2 shall be wider than the rail base to permit the plate 2 to be slid inwardly far enough to readily detach the plate from the rail.

Having thus described my invention, what I claim as new and desire to secure by Letters Patent, is:

1. A rail joint comprising a rigid member formed with a base support wider than the rail base and with an upwardly extending rail supporting flange adapted to support the head of the rail, and a swinging clamping member hinged to the edge of the base support and formed with an outwardly extending tie engaging part and an inwardly extending rail engaging part, said base support and said clamping member being provided with registering spike-holes at a point between the hinge and the rail base.

2. A rail joint comprising a rigid member formed with a base support and a rail supporting part, a substantially cylindrical hinge bead or rib formed on the free edge of the base support, said base support being broader than the rail base and the hinge bead being raised above the plane of the rail base, and a swinging clamping member provided with a groove adapted to receive the hinge rib whereby the clamping member will be locked to the rigid member, said clamping member being formed with an outwardly extending rail engaging part.

3. A rail joint comprising a rigid member formed with a base support and a rail supporting part, a substantially cylindrical hinge bead or rib formed on the free edge of the base support, said base support being broader than the rail base and the hinge bead being raised above the plane of the rail base, a swinging clamping member provided with a groove adapted to receive the hinge rib, whereby the clamping member will be locked to the rigid member, said clamping

member being formed with an inwardly extending rail engaging part and an outwardly extending tie-engaging portion.

4. A rail joint comprising a rigid member 5 formed with a base support and a rail supporting part, a substantially cylindrical hinge bead or rib formed on the free edge of the base support, said base support being broader than the rail base, a swinging clamping member provided with a groove adapted 10 to receive the hinge rib, whereby the clamping member will be locked to the rigid member, said clamping member being formed

with an inwardly extending rail engaging part, and an inwardly extending lug formed 15 on the hinge rib, the swinging clamping member being formed with a recess adapted to receive said lug when said member is in engagement with the rails.

In testimony whereof I hereunto affix my 20 signature in the presence of two witnesses this 29th day of May, 1908.
